COMBINED PENCIL HOLDER AND SHARPENER

Filed Dec. 11, 1928

UNITED STATES PATENT OFFICE

JACOB M. STONE, OF EL DORADO, ARKANSAS

COMBINED PENCIL HOLDER AND SHARPENER

Application filed December 11, 1928. Serial No. 325,239.

The invention relates to pencils and has as an object the provision of a combined holder and sharpener.

It is a further object of the invention to 5 provide a holder for a pencil carrying a pencil sharpener and having means to feed the pencil through the sharpener whereby the point may be exposed for use.

It is a further object of the invention to 10 provide a clip carried by the holder and foldable to position for retaining the holder in the pocket of the user and also movable to a position to serve as a handle in the operation of sharpening the pencil.

15 It is a further object of the invention to provide a holder in the form of a cover for the pencil whereby the pencil may be used down to a short length, the holder providing means of unchanging length for manipulation of the pencil.

Further objects of the invention will appear from the following description when read in connection with the accompanying drawings showing an illustrative embodiment of the invention and wherein:

Fig. 1 is a side elevation showing the clip folded upon the pencil;

Fig. 2 is a side elevation upon an enlarged scale partly broken away and showing the clip extended to serve as a handle for the pencil sharpener; and

Figs. 3, 4, and 5 are horizontal sections on lines 3—3, 4—4, and 5—5, respectively, of Fig. 1.

As shown the device comprises a tubular envelope 10 desirably formed of thin metal having internal grooves 11, shown as two in number, desirably formed by outwardly pressing the metal of the envelope, the external ribs 12 produced in the formation of the internal grooves desirably terminating at a point as 13 midway of the length of the pencil, thus producing slots 14 through a portion of the length of the envelope, the separation of the envelope by the slots 14 providing a spring action to the lower portion of the envelope.

A pencil sharpener is shown in the form of a conical portion 15 having a cutting edge 16 of a usual form but in the present in-

vention assuming the form of a spiral upon the conical portion 15, the point of the cone 15 being cut away at 17 to permit the point of the pencil to protrude. The pencil sharpener further comprises a cylindrical portion 18 which may be joined to the portion 15 as by right hand threads 19 or which may be brazed or soldered to the conical portion 15 if desired.

The cylindrical portion 18 of the sharpener is shown as formed with a groove 19 adjacent its open portion cooperating with an internal bead 20 upon the ends of the portions into which the member 10 is separated by the slots 14.

To feed the pencil through the sharpener the cylindrical portion 18 is shown as formed with internal sharpened threads 21 which cut into the wood of the pencil, producing threads in the wood thereof, and thereby feeding the pencil to the sharpening edge 16 causing the lead to project through the opening 17.

To cause revolution of the pencil in the cylindrical portion 18 and threads 21, there is shown a cap 22 having sharpened internal threads which is to be screwed upon the upper end of the pencil 23 preparatory to introducing the same into the holder. The cap 22 is shown as formed with wings 24 desirably formed by an outward deformation of the material of cap 22 but which may be formed by adding material to the outside of the cap. The wings 24 are adapted to slip into the slots 14 and into the internal grooves 11, the cap 22 telescoping within the cap 10.

An eraser 25 may be inserted in the open end of the tubular member 10.

A combined clip and handle for the sharpener is shown in the form of a member 26 desirably having its body internally concave so as to fit against the surface of member 10 and provided with a pair of ears 27 pivoted upon the exterior of cylinder 18. As shown the ears 27 are perforated, which perforations engage studs 28 carried by the cylinder 18 at diametrically opposite points.

The body of member 26 is shown as terminating at 29 to permit the member 26 to swing to a position perpendicular to the de-

vice and the device when folded occupies the position shown in Fig. 1 with the member 26 in contact with the holder.

To retain the clip in the position shown in Fig. 1, the member 26 is shown as provided with lips 30 having their ends 31 outwardly flared so as to snap about the body of the tubular member. The member 26 is provided with the pocket clip member 32 to engage over the edge of a pocket of the user. While the sharpener bearing the member 26 is shown in combination with the tubular container 10 it will be obvious that the sharpener and clip may be applied to a pencil without the member 10, the lips 30 then engaging the surface of the pencil itself when in the position of Fig. 1, and still secure some of the advantages of the invention. Therefore where in the following claims it is recited that the member 26 is in contact with the pencil, the tubular member 10 is to be read as "the pencil" for purposes of coaction with the member 26 and lips 30.

Since the internal threads of the cap are of the same character as those at 21 in the sharpener, as for instance both right hand threads, any tendency of the cap to revolve upon the pencil will only tighten the same thereon. The cap may therefore be regarded as rigidly mounted on the pencil. While screw threads have been shown for purposes of illustration, as a mounting for the cap, other forms of non-rotatable mounting may obviously be utilized.

In operation the cap 22 is screwed upon the end of a pencil and the end to be sharpened is inserted into the cylinder which is screwed thereon until the pencil is sharpened whereupon the pencil and cap 22 are introduced into the tubular element 10 with the wings 24 lying in the internal grooves 11. The ends of the tubular envelope by virtue of the spring action provided by slots 14 are then snapped upon the end of the sharpener.

When it is desired to sharpen the pencil to feed more lead from the opening 17, the clip member 26 is swung to the position shown in Fig. 2 and utilized as leverage to hold the sharpener stationary, revolution of member 10 causing revolution of the pencil within the threads 21 to feed the pencil through the sharpener. The clip 26 may be then swung to the position shown in Fig. 1 and placed in the pocket of the user, the member 32 thereof engaging over the edge of the pocket to prevent escape therefrom.

Minor changes may be made in the physical embodiment of the invention within the scope of the appended claims without departing from the spirit thereof.

I claim:

1. A combined pencil sharpener and clip comprising, in combination, a sharpener having a cutting edge and internal screw threads adapted to cut into the wooden portion of a

pencil and thereby feed the pencil against the cutting edge, a member pivoted on said sharpener to swing to a position perpendicular to the pencil and to a position in contact therewith, a pair of clips carried by the member adapted to engage about the pencil to hold the member in contact therewith.

2. A combined pencil holder and sharpener comprising, in combination, an internally screw threaded sharpener, a pencil holder revolubly mounted upon said sharpener, means independently mounted upon a pencil adapted to telescope in said holder and means to prevent relative rotation between said pencil carried means and said holder.

3. A combined pencil holder and sharpener comprising, in combination, a sharpener having a cutting edge and internal screw threads to feed a pencil to said cutting edge, a tubular casing removably and rotatably engaging said sharpener, said casing having internal longitudinal grooves, a cap rigidly engageable with the pencil and telescoping in said casing, projections carried by the cap slidable in said grooves whereby rotation of the casing relative to the sharpener will feed the pencil to said cutting edge.

4. A combined pencil holder and sharpener comprising, in combination, a sharpener having a cutting edge and internal screw threads to feed a pencil to said cutting edge, a tubular holder member removably and rotatably engageable with said sharpener, a cap member to be rigidly mounted on a pencil, said cap and pencil telescoping with said tubular member, one of said members provided with a longitudinal groove and the other member with a projection sliding in said groove to prevent relative rotation between said members whereby relative rotation between said holder and sharpener may feed the contained pencil through the sharpener.

5. A combined pencil holder and sharpener comprising, in combination, a sharpener having a cutting edge and a cylindrical portion formed with internal cutting screw threads to feed a pencil to the cutting edge, a holder having a longitudinal slot to provide a resiliently expandible portion at an open end, a circumferential bead and a circumferential groove one carried by each of said portions coacting to mount the holder removably and rotatably upon the sharpener, an internal groove in said holder forming a continuation of said slot, a cap to be rigidly mounted on the pencil and a projection carried by the cap slidable in the slot and groove to prevent relative rotation between the pencil and holder.

6. A combined pencil holder and sharpener comprising, in combination, a sharpener element having a cutting edge and internal cutting, pencil feeding screw threads, a holder element rotatably mounted on the sharpener, a member to be non-rotatably mounted on a

pencil and with the pencil slidable within the holder, means to prevent relative rotation between the holder and member, a clip member pivoted upon one of said elements to swing to a position to serve as a handle while rotating one of said elements relative to the other thereof while sharpening the pencil and to a pocket engaging position in contact with one of said elements.
